MEANS FOR FEEDING PARGETING MACHINES WITH THICK PARGETING MATERIAL

Pierre Michel Jean Marie Raymond Daignas, Nice, France

Application June 16, 1953, Serial No. 362,019

Claims priority, application France June 19, 1952

10 Claims. (Cl. 299—63)

When it is desired to project coating material, such as a mortar including sand with a view to producing a mottled effect, it is generally necessary to resort to pargeting machines including a casing into which pargeting material is fed and inside which revolves a throwing rotor provided with flexible radial blades the free ends of which, during the rotation of said rotor are successively in scraping engagement with an abutment which curves them before they pass in register with an exhaust opening, whereby said blades, which have during their travel picked up in the casing a certain amount of pargeting material, are suddenly released by escaping from the abutment and project energetically the material carried by them through the exhaust opening.

Generally speaking, such pargeting machines produce a reliable projection of material only if the casing wherein the rotor moves is but slightly laden with material to be projected, or if said material is sufficiently fluid. It is consequently necessary to load the machine to a moderate extent and this necessity is detrimental to its efficiency.

On the other hand, it may be of interest to use such pargeting machines for projecting thick paints with a view to produce a mottled relief effect. But such heavy paints, such as those having as a base plastic material, are generally fibrous because they include asbestos or cellulosic fibres and, by reason of the compact structure of these paints, the blade-carrying rotor is speedily crammed if it is loaded under normal conditions with such thick material.

My improved method for feeding projecting machines of the above type allows removing the above drawbacks and, according to said method, the throwing rotor is separated from the provision of material to be projected and the amount of material picked up by the successive blades on the rotor is dosed so as to correspond to the desired value.

My invention has furthermore for its object an arrangement for the execution of the above method. Said arrangement includes a compartment that is separated from the area swept over by the rotor blades by means of a grid-shaped partition substantially tangent to the path followed by the ends of the projecting blades while a movable member is associated with said separate compartment with a view to urging through the grid, as requested by the operator, a fraction of the thick pargeting material introduced into said compartment which acts as pargeting material receptacle. The separate compartment may be constituted by an auxiliary container removably fitted inside the actual casing of the pargeting machine or it may be defined in said casing by a mere perforated partition, such as said grid-shaped partition, fixed in said casing so as to define a space that is not swept over by the projecting means and that is adapted to receive the load of pargeting material to be projected.

According to an advantageous embodiment of my invention, the movable member which is intended to provide for the dosing of the pargeting material through the grid towards the blades of the throwing rotor, is con-

2

stituted by a movable flap revolvably carried by a spindle parallel to the axis of rotation of said rotor, said flap being controlled by a rod pivotally secured thereto and the free end of which is preferably actuated by the thumb 5 of the operator's hand which carries the pargeting machine through its gripping means. The meshes of the grid are sufficiently close so that the passage of the thick pargeting material contained in the compartment under the sole action of gravity is avoided. The throwing rotor can therefore be fed only when the operator exerts a pressure on the movable flap and thus the feeding of pargeting material to said rotor stops as soon as the pressure ceases. This leads to a uniform feed the rate of which is entirely controlled by the operator. The machine executed as disclosed allows projecting not only semi-liquid material but also very thick material while the machine may be fully loaded whatever may be the viscosity of the pargeting material.

Preferably the pargeting machine is of the type described in my French Patent No. 781,052, filed on January 27, 1934, or in the first certificate of addition No. 47,767, therefor filed on February 28, 1936; said machine may include the improvements described in my French Patent No. 851,673, filed on September 26, 1938, and in my French Patent No. 1,053,444, filed on April 4, 1952.

The following description and accompanying corresponding drawings are given by way of a mere exemplification and by no means in a binding sense so as to allow 30 ascertaining the manner of executing my invention, the features disclosed forming part of my invention insofar as they are claimed in accompanying claims.

To make the disclosure easier, the means for feeding semi-liquids or very thick material to the machine rotor 35 will be termed hereinafter the pusher. In accompanying drawings:

Fig. 1 is a side view, partly torn off, of a pargeting machine including a container for pargeting material to be projected and provided with a pusher in accordance 40 with my invention.

Fig. 2 is an outer front sectional view of the machine illustrated in Fig. 1, as seen from the side provided with the exhaust opening, certain parts being shown as torn off.

Fig. 3 is a perspective view of the pusher, shown separate, provided on the machine illustrated in Fig. 1.

Fig. 4 is a perspective view of a modified pusher.

Fig. 5 is an outer side view on a smaller scale of a pargeting machine provided laterally with an auxiliary 50 container for a provision of pargeting material to be projected, said machine incorporating a pusher.

Turning to Figs. 1 and 2, the machine illustrated includes a casing 1 having an upper wall 2, a rear cylindrical wall 3, a bottom wall 4 extending forwardly up to an exhaust opening 5 and two side-walls 6 and 7, said casing receiving the pargeting material to be projected. Inside said casing is revolvably mounted a throwing rotor constituted by a drum 8 carrying projecting blades 9 associated with a cross bar 10 forming an abutment. Said blades 9 are arranged in the manner disclosed in my above-mentioned French Patent No. 1,053,444; the drum 8 is rigid with a spindle 11 revolvably carried in bearings 12 secured to the side-walls 6 and 7 of the casing. A driving crank 13 is keyed to said spindle (Fig. 1). The ends of the 60 throwing blades 9 are tensioned by an abutment constituted by a plate 14 secured to a shaft 15 parallel with the rotor spindle 11 and carrying outside the casing a radial arm 16, the end 17 of which is adapted to engage the teeth of a quadrant 18 secured to the side-wall 7. This arrangement allows a speedy and accurate control of the position of the abutment plate 14. An arm 19 loosely mounted on shaft 15 is provided with a suitably shaped cut flexible

tongue 20 that is folded so as to project from the arm 19 and is also adapted to engage the teeth of quadrant 18, said tongue acting as a terminal abutment for the movements of the arm 16.

Inside the casing 1 is housed a pusher constituted by a small vat 21 the rear wall of which is open, said pusher being provided with a front hook-shaped edge 22 which engages the incurved front edge 23 of the bottom wall of said casing 1, said edge 23 defining the lower end of the exhaust opening 5; the rear edge of the vat 21 forms a supporting member 24 resting on the bottom 4 of the casing. The vat 21 is closed at its rear end by a grid 25 the meshes of which are rather close, said grid being carried by a frame 26 having two lateral rabbets 27 which are adapted to slide over the inturned edges 28 of the side walls of the vat 21 (Fig. 3) so as to allow an easy removal of the grid either for inserting a grid having a different size of mesh or else in order to clean the said grid. A transverse spindle 29 is secured between the side walls of the vat 21 and to said spindle is rockably secured a flap 30 extending across the vat 21 and controlled by a rod 31 pivotally secured to a carrier member 32 rigid with the flap surface. Said rod 31 passes through an opening 33 (Fig. 1) provided in the upper wall 2 of the machine casing and its upper end 34 is threaded as shown in Fig. 2 so as to receive the tapped control knob 35.

When it is desired to project semi-liquids or highly viscous material, the pusher is fitted in the pargeting machine, as provided by inserting the rod 31 into the port 33 after unscrewing the knob 35 and by fitting the vat 21 inside the front section of the casing. After raising the flap 30, the operator loads the vat 21 with the pargeting material to be projected. While he is holding the machine through the handle 36 (Fig. 1), he may depress the flap 30 through action on the knob 35 so as to adjust the amount of material discharged through the grid 25 the position of which is substantially tangent to the path followed by the ends of the blades 9 on the rotor 8.

The removal of the pusher is performed through a mere raising movement without any tool being required and it is sufficient to this end to remove the control knob 35 carried by the rod 31 before raising the pusher out of the casing 1.

The arrangement illustrated in Fig. 4 may be used instead of the pusher shown as fitted inside the machine of Figs. 1 and 2. This arrangement includes a grid 25a the frame 26a of which may slide between two folded metal sheets 37 carried by the carrier 38 constituted by a bent wire. Said carrier is provided with two eyes 39 inside which is mounted a sleeve 40 extending over the upper edge of the grid and adapted to carry a spindle 41 one end of which extends at right angles to its main section as shown at 42 while its other end is threaded and carries a wing nut 43. To the sleeve 40 is hingedly secured by means of two hinge knuckles 44 a flap 30a rigid with a carrier member 32a to which is pivotally secured a control rod 31a. The wire carrier 38 includes two extensions 45 projecting beyond the eyes 39 and the ends of which 46 are hook-shaped. For the mounting of this arrangement, the side walls 6 and 7 of the machine illustrated in Figs. 1 and 2 are cut out so as to form the openings required for the passage of the spindle 41 over which is fitted the sleeve 40 provided with its flap 30a, said spindle being held in position by a tightening of the nut 43 over it. Two further openings are provided in the flanges 6 and 7 for engagement by the hook-shaped ends 46 of the carrier 38 so as to form a rigid unit with the machine casing by reason of the hooking engagement thus obtained.

The machine operates in the same manner as that described with reference to Figs. 1, 2 and 3, the material-containing vat being constituted by the section of the casing comprised between the grid 25a which engages the casing bottom 4, the front raised end of said bottom section and the side-walls 6 and 7.

The pusher may be located as shown in the modification

of Fig. 5 in adjacent relationship with the casing that is coaxial with the projecting rotor. This is the case of the pargeting machine 47 illustrated diagrammatically in Fig 5. The vat 21b is then housed outside the actual machine and is secured by means of a hook 48 engaging the inside of the machine so that said vat registers with an opening formed in the outer cylindrical wall of the machine 47. The vat 21b is on the other hand carried by a spindle passing through the fittings 49 carried on the outside of the machine 47 and to which may be secured a rod carrying a section of the wall 50 revolvably carried round the spindle 51 of the machine. Thus, when the pusher is not in use, the wall section 50 closes the opening in the machine 47, which registers with the vat 21b. The remainder of the arrangement is similar to that disclosed with reference to Figs. 3 and 4, the spindle 31b controlling the location of the flap 30b with reference to the grid 25b.

Obviously, without unduly widening the scope of the invention as defined in accompanying claims, numerous modifications may be brought to the arrangements disclosed.

What I claim is:

1. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises a grid-shaped partition removably mounted within the casing, contacting the bottom thereof and substantially tangent to the path followed by the free ends of the flexible blades, whereby a thick pargeting material may be stored into said casing without contacting said flexible blades, and means for urging through said grid a fraction of the stored thick pargeting material when a pargeting operation is to be performed.

2. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises a separate vat adapted to contain thick pargeting material and opening in register with the periphery of the rotor, a grid-shaped member extending across the opening of the vat, a movable member carried inside said vat, and means controlling the movement of said movable member towards the grid to urge the thick pargeting material through said grid-shaped member towards the flexible blades of the rotor for subsequent projection by said blades.

3. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises an auxiliary vat adapted to contain thick pargeting material, removably fitted inside the casing on the outside of the path of the rotor blades and provided with an opening facing the latter, a grid extending over the opening of the vat in a direction tangential with reference to the path of said rotor blades, a movable

member carried inside said vat, and means controlling the movement of said movable member towards the grid to urge the thick pargeting material through said grid towards the blades of the rotor for subsequent projection by said blades.

4. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises a grid extending in substantial tangential relationship with reference to the path of the rotor blades and defining on the outside thereof and within the casing a vat section adapted to be filled with the thick pargeting material to be projected, a movable member carried inside said vat section and means controlling the movement of said movable member towards the grid to urge the thick pargeting material through said grid towards the blades of the rotor for subsequent projection by said blades.

5. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises an auxiliary vat adapted to contain thick pargeting material, removably fitted inside the casing on the outside of the path of the rotor blades and opening in register with the periphery of the rotor, a grid extending across the opening of the vat, a spindle carried by the vat parallel with the axis of rotation of the rotor and located on the outside of the latter, a flap revolvably carried by said spindle and engaging the inside of the vat in register with the grid, a rod pivotally secured to said flap to control the movements of the latter towards the grid to urge the thick pargeting material through the opening in the vat towards the blades of the rotor for subsequent projection by said blades, and a hand-operable member at the free end of the control rod located in the vicinity of the gripping means of the machine.

6. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises an auxiliary vat adapted to contain thick pargeting material, removably fitted inside the casing on the outside of the path of the rotor blades and opening in register with the periphery of the rotor, a grid extending across the opening of the vat, the meshes of which grid are close enough to prevent the thick pargeting material contained in said vat from entering under the sole action of gravity the fraction of said casing containing the rotor, a movable member carried inside the vat, and means controlling the movement of said movable member towards the grid to urge the thick pargeting material through said grid towards the blades of the rotor for subsequent projection by said blades.

7. In a pargeting machine utilizing semi-liquid and viscous pargeting material and of the type comprising

a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises an auxiliary vat adapted to contain thick pargeting material, removably fitted inside the casing on the outside of the path of the rotor blades and opening in register with the periphery of the rotor, a removable interchangeable grid extending across the opening of the vat, a movable member carried inside said vat, and means controlling the movement of said movable member towards the grid to urge the thick pargeting material through said grid towards the blades of the rotor for subsequent projection by said blades.

8. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises an auxiliary vat adapted to contain the thick pargeting material, removably fitted inside the casing on the outside of the path of the rotor blades and provided with an opening facing the latter, means rigidly carried by said vat and adapted to be removably hooked onto the casing, a grid extending over the opening of the vat in a direction tangential with reference to the path of said rotor blades, a movable member carried inside said vat, and means controlling the movement of said movable member towards the grid to urge the thick pargeting material through said grid towards the blades of the rotor for subsequent projection by said blades.

9. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises an auxiliary vat adapted to contain thick pargeting material, removably fitted inside the casing on the outside of the path of the rotor blades and provided with an opening facing the latter, a grid extending over the opening of the vat in a direction tangential with reference to the path of said rotor blades, a movable member carried inside said vat, means controlling the movement of said movable member towards the grid to urge the thick pargeting material through said grid towards the blades of the rotor for subsequent projection by said blades, a frame carrying the grid, the movable member and the means controlling the latter, said frame resting on the bottom of the casing and carried inside the latter on the outside of the rotor, and means for detachably securing the frame and the controlling means to the casing.

10. In a pargeting machine utilizing semi-liquid and viscous pargeting material and of the type comprising a casing provided with gripping means and into which pargeting material is stored and with a throwing rotor formed with flexible blades which, during the rotation of said rotor are in scraping engagement by their free ends with an abutment which curves them, the releasing of the flexible blades when they escape from said abutment causing a projection of the pargeting material picked up by the ends of said flexible blades; the improvement which comprises, a cylindrical casing formed with

two openings in its cylindrical wall, one of which acts as pargeting opening, an auxiliary vat removably secured to the outside of the cylindrical wall of the casing in register with the second opening therein and adapted to contain thick pargeting material, a grid covering said second opening, a movable member carried inside said vat, means controlling the movement of said movable member towards the grid to urge the thick pargeting material through the second opening towards the blades of the rotor for subsequent projection through the first opening of said casing, and a wall adapted to removably

5

10

close the second opening of the casing when the machine is not operative.
